UNITED STATES PATENT OFFICE.

JAMES ATKINSON DOUGLAS, OF WINNIPEG, MANITOBA, CANADA.

SPEED-REGULATOR.

1,185,887.

Specification of Letters Patent.

Patented June 6, 1916.

Application filed August 31, 1914. Serial No. 859,394.

To all whom it may concern:

Be it known that I, JAMES ATKINSON DOUGLAS, of the city of Winnipeg, in the Province of Manitoba, Canada, have invented certain new and useful Improvements in Speed-Regulators, of which the following is the specification.

The invention relates to improvements in speed regulators and the object of the invention is to provide a mechanism by means of which a driven shaft can be driven by a drive shaft at any speed from zero to maximum positive and zero to maximum negative and can be retained operating at any constant selected speed as desired by the attendant.

A further object of the invention is to provide a mechanism which will allow of the above range of speeds in the driven shaft without the use of varying speed gears as are customarily employed where a range of speed in a driven shaft is required.

With the above objects in view the invention consists essentially in the arrangement and construction of parts hereinafter more particularly described and later pointed out in the appended claims.

Figure 1 represents a plan view of the complete machine, the top of the framework being removed. Fig. 2 is a longitudinal vertical sectional view centrally through the machine. Fig. 3 represents a rear view of the slotted plate and adjoining parts, certain of the parts being shown in vertical section. Fig. 4 represents an end view of the machine, the front bearing being shown in dotted outline. Fig. 5 represents a vertical sectional view through the machine, the section being taken in the plane denoted by the line X'-X' and looking in the direction indicated by the arrow "a" Fig. 2. Fig. 6 represents an enlarged detailed vertical sectional view through the disk and associated parts. Fig. 7 represents a vertical sectional view through the machine, the section being taken in the plane denoted by the line Y'-Y' and looking in the direction indicated by the arrow "b" Fig. 2. Fig. 8 is a vertical sectional view through a portion of the slotted plate, the section being taken in the plane denoted by the line Z-Z' Fig. 3.

In the drawings like characters of reference indicate corresponding parts in each figure.

55 1 represents a suitable base plate mounted

on a permanent understructure 2, 3, 4 and 5 represent similar standards permanently fastened to the base plate by bolts 6 and presenting alined bearings 7, 8 and 9 for parts later described.

60 10 represents a substantially rectangular open stationary framework erected on the base plate and located between the standards 3 and 4. This framework comprises suitably connected side bars 10' and 10" and a 65 connecting cross bar 10'.

11 is a guide bar elevated above and secured to the base plate and passing in a direction across the machine, the said bar being contained within the plane containing 70 the cross bar 10'. Directly beneath this guide bar the base plate is slotted as shown at 12, the slot accommodating certain parts later described.

13 is a horizontally disposed substantially 75 rectangular guide frame contained within the framework and carrying a pair of upwardly and downwardly projecting guide rods 14 and 15, the guide rods being slidably received within the bars 10' and 11 and 80 having their extremities projecting beyond said bars.

16 is a vertically disposed substantially 85 rectangular guide frame located in the open center of the framework and provided with 90 horizontally disposed extending guide rods 17 and 18 which are carried slidably by the side bars 10' and 10" of the frame and have their ends projecting beyond the said bars. The guide frames are identical in construction and are arranged so that one is immediately to the side of the other with the adjacent faces bearing slidably one on the other. The rods 14 and 15 are alined vertically while the rods 17 and 18 are alined 95 horizontally and they are arranged such that if their inner ends were projected they would intersect at a point alined with the longitudinal axis of the several bearings, hereinbefore mentioned, of the standards. 100

19 is a flat square carrying block mounted within the horizontally and vertically disposed portions of the guide frames as best shown in Fig. 2 of the drawings. According to the above construction the position of the carrying block can be varied within the framework as the guide frames will slide to accommodate the movement of the block. 105

20 is a circular disk rotatably mounted 110 within the carrying block.

21 is a drive shaft rotatably mounted in the standards 4 and 5 and having the inner end thereof terminating at the disk.

22 is a drive pulley permanently secured to the outer end of the shaft and 23 is a collar fixed thereon immediately adjoining the inner face of the bearing 7.

24 is a slotted plate permanently secured by means of a key 25 to the inner end of the shaft 21. The inner face of this plate is slidably engaged with the adjoining face of the disk and carrying block as well as with the adjoining face of the guide frame 16.

26 and 27 are parallel slots passing through the plate 24 and located at opposite sides of the center thereof and 28 is a further centrally located slot parallel with the other slots and passing in a direction from the center of the plate to the periphery thereof.

29, 30 and 31 are guide pins projecting from the face of the disk and received slidably within the slots 26, 27 and 28 respectively. The pins 29 and 30 are supplied with retaining washers and 32 and 32' held in position against the outer face of the plate 24 by means of screws 33. The pin 31 is supplied with an enlarged shoulder 34 bearing also against the outer face of the plate and is fitted further with an enlarged head 35 supplied with a screw threaded opening 36 for a purpose later explained. These pins form a connection between the disk and the plate and owing to the pins being restricted in their movement within the slots it will be seen that the disk can only be adjusted in a radial direction in respect to the plate.

37 is an inner sleeve mounted rotatably on the shaft 21 between the bearing 8 and the outer face of the plate. The sleeve is supplied at the outer end with a gear wheel 38 and at the inner end with a bevel wheel 39, the arrangement being such that when the gear wheel is turned the bevel wheel is caused to rotate through the sleeve connection.

40 is an outer sleeve rotatably mounted on the inner sleeve and having the inner end butted against the face of the bevel wheel 39 and the outer end supplied with a gear wheel 41 and an associated bevel wheel 42, the outer faces of the gear wheel bearing frictionally against the inner face of the wheel 38. The bevel wheels 39 and 42 are similar and are disposed directly opposite to one another and are both continuously in mesh with a bevel pinion 43 permanently mounted on the inner end of a screw threaded shaft 44 which threads through the opening 36 in the head 35 hereinbefore mentioned.

45 is a bearing secured to the rear face of the slotted plate and carrying the inner end of the shaft 44. This bearing is constructed so that the shaft can rotate freely but cannot move endwise.

46 is a counter shaft located beneath the drive shaft 21 and parallel with the same, said counter shaft protruding through the standard 4 and having the inner end carried by a bearing plate 47 secured to the standard and the outer end mounted in a specially constructed friction member 48 fastened to the standard by a pin 49.

50 is a friction disk having the faces thereof oppositely coned as indicated at 50' and 50². The friction member 48 is supplied with opposing coned recesses 51 and 52 designed to receive the oppositely coned faces of the disk upon the counter shaft being shifted endwise as later explained. The inner end of the counter shaft carries a pinion 53 designed to engage with one or other or both of the gear wheels 38 and 41, depending on the shifted position of the counter shaft.

54 is a pivoted controlling lever having the upper end thereof forked and spanning the outer end of the counter shaft, the forked end operating between two permanent collars 55 and 56 fastened to the said shaft.

By the above arrangement it is possible to change the position of the disk radially in respect to the slotted plate while the drive shaft is being rotated by simply manipulating the lever. If the lever be thrown to the position shown in Fig. 2 of the drawings to bring the coned face 50² into engagement with the coned recess 52, the pinion 53 is engaged with the gear wheel 38 and accomplishes the object of locking said gear wheel against rotation, this being due to the frictional contact between the coned disk and the member 48. Accordingly when the drive shaft is rotated the pinion 43 is controlled by the bevel wheel 39 which is obviously locked when the gear wheel 38 is locked. In the continued right hand rotation of the drive shaft the locked bevel wheel 39 will have the effect of turning the bevel pinion 43 in a direction which will cause the head 35 to draw in on the screw threaded rod with the result that the disk will be drawn in toward the center of the slotted plate. On the other hand if the lever be thrown to the opposite position to that shown in Fig. 2 to bring the pinion 53 into engagement with the gear wheel 41 and the coned face 50' into engagement with the coned recess 51 then the gear wheel 41 will be locked against rotation in respect to the drive shaft as will also the bevel wheel 42.

In the continued right hand rotation of the drive shaft the pinion 43 will then operate on the bevel wheel 42 in a manner such that the screw shaft 44 will force the head 35 outwardly and accordingly pass the disk in a radial direction toward the periphery of the slotted plate. Further if the lever be thrown to a central position to engage

the pinion 53 with both of the gear wheels 38 and 41, then there will be no relative movement allowed the gear wheels with the result that the pinion 43 will be locked between the bevel wheels 39 and 42. In the rotation of the drive shaft there will accordingly be no movement transmitted to the screw shaft 44. The disk will consequently remain in whatever position it occupies at the instant the lever is brought to central position.

The detailed construction of the above explained parts for changing the position of the disk in respect to the plate, while rotating the shaft could be readily modified without departing in the least from the spirit of the invention. They are only shown as a means for accomplishing the radial adjustment of the disk. In actual practice in some machines the locked gear construction could be entirely dispensed with and a crank applied on the outer end of the screw shaft. This would allow of the adjustment but it would be necessary to stop the rotation of the shaft to effect the adjustment.

57 is a driven shaft rotatably mounted in the bearing provided in the standard 3. This shaft is alined with the drive shaft 30 and is supplied at the outer end with a pulley 58 and at the inner end with a bevel wheel 59, the pulley and wheel being fixed to the shaft.

60 is a controlling wheel rotatably mounted on a permanent pin 61 extending from the inner face of the disk. For reasons later explained this pin is located slightly eccentric to the center point of the disk, this being best shown in Fig. 4 of the drawings where "c" represents the center point of the disk and "d" the center point of the pin. The controlling wheel embodies in its structure a gear wheel 62 and a bevel wheel 63 which cooperate with parts later described.

64 is a boss permanently secured to the extending end of the pin and carrying an opposing pair of arms 65 and 65', the arms being secured to the opposite sides of a substantially rectangular sliding frame 66 mounted on a rectangular carrying block 67, the block being rotatably mounted on an extending boss 67' formed as a part of the standard 3 and the bearing 9.

68 is a square cross shaft having the ends rounded and rotatably mounted in bearing arms 69 and 69' extending inwardly from the ends of the frame 66. The cross shaft is disposed at right angles to the shaft 57 and intersecting the projected axis of the same. It carries a sliding pinion 70 which is held constantly in mesh with the bevel wheel 59 by the action of an arm 71 extending from the carrying block 67. In the actual construction it will be seen that the forward end of the latter arm receives rotatably a boss 70' extending

from the pinion and that it is split vertically to admit an outstanding collar 70" carried by the boss. The cross shaft is accordingly free to move endwise in respect to the pinions but will drive the pinion in any position.

72 is a second pinion permanently secured to the cross shaft and opposing the pinion 70. The pinion 72 meshes continuously with the bevel wheel 63 of the controlling wheel. In this connection it is pointed out that while the controlling wheel may change its position as controlled by the pin, in a radial direction in respect to the common longitudinal axis of the drive and driven shafts, still the pinion 72 will always remain meshed with the controlling wheel as the sliding frame 66 carrying the square shaft which carries the said pinion moves with the pin to which it is permanently attached as already explained.

73 is a circular ring located in advance of the carrying block 19 and permanently secured to the same by screws 74. The ring is arranged concentric to the disk.

75 and 76 are opposing vertically disposed toothed locking dogs located at the inner ends of shanks 77 and 78, said shanks having their outer ends slidably received within brackets 79 and 80 permanently secured to the outer ends of the rods 14 and 15 and their inner ends slidably mounted in further brackets 81 and 82 extending from the guide frame 13. 83 and 84 are further opposing horizontally disposed toothed locking dogs located at the inner ends of extending shanks 85 and 86 having their outer ends slidably mounted in brackets secured to the outer ends of the rods 17 and 18 and similar to those 79 and 80 and their inner ends slidably mounted in further brackets extending from the guide frame 16 and similar to those 81 and 82. The dogs are contained in the same vertical plane as the gear wheel 62 and the carrying shanks if projected are designed to intersect on the common longitudinal axis of the drive and driven shafts. Each shank carries a sliding sleeve 87 which is connected pivotally in each instance to the outer end of an adjustable link 88 having the inner end pivotally fastened by means of a pin 89 to the ring 73.

90 are stop plates mounted on the outer ends of the respective shanks and engaged with stop pins 90' passed through the shanks.

91 are springs mounted on the shanks and having their outer ends bearing against the sleeves 87 and their inner ends engaging with stop collars 92 held by pins 93 passed through the shanks.

94 is a counterbalancing weight having the base thereof dovetailed as indicated at 94' and slidably received within a complementary channel 95 formed in the outer face 130

of the plate 24. The channel is diametrically opposite the slot 28.

96 is a bevel pinion meshing with the bevel wheels 39 and 42 and located at the 5 inner end of a screw threaded shaft 97 which passes through a screw threaded opening 94² located in the counter balancing weight.

The inner end of the shaft is rotatably 10 mounted in a suitable bearing 98 similar to that 45 secured to the outer face of the plate 24. The object of this weight is to automatically counterbalance the swinging parts of the machine as controlled by the adjusting shaft 44. It will be seen that as the 15 pinion 96 meshes with the same wheels as the pinion 43 the shaft 97 will be turned each time the shaft 44 rotates with the result that the counter-balancing weight will 20 be forced in and out on the shaft 97 an equal amount to the adjustment given the head 35 and associated parts.

In Fig. 4 of the drawing the position of the moving parts has been changed from 25 the position occupied by them in the other figures. This change of position is made so that the operation and movement of the parts may be better understood.

To understand the operation of the device I wish to point out that there are what 30 might be termed three controlling positions which the pin carrying the controlling wheel may have. The first position is that in which the screw shaft 44 has been 35 adjusted so that the center of the pin 61 lies on the longitudinal axis of the drive shaft. The second position is that when by the adjustment of the said screw shaft the pin 61 is brought to a position wherein it is 40 passed in one direction away from the axis of the drive shaft and the third position is that wherein the pin has been adjusted by means of the said screw such that it is passed in the opposite direction from the 45 center point or axis of the drive shaft. To understand this, reference is made to Fig. 3 of the drawings wherein it will be seen that if the screw be turned in a proper direction the pin 61 as shown in dotted line 50 will be brought in until it is concentric to the drive shaft. This is the first position above referred to. The position which the said pin occupies in Fig. 3 is one of the various positions which it may have in the 55 second controlling position referred to above. If the screw be turned in a proper direction to pass the center of the pin 61 to the other side of the drive shaft to that shown in Fig. 3, then the said pin will occupy 60 one of the various adjusted positions which it may have when in the third controlling position above described. Assuming then the drive shaft rotated at a constant speed. In the first or central position 65 of the pin the driven shaft is rotated at a

constant speed faster than the drive shaft, the speed of rotation depending entirely on the ratio of the wheels 63, 72, 70 and 59. In the second position the driven shaft will be rotated at a speed slower than in the first 70 position, the speed of the driven shaft decreasing each time adjustment is made to pass the pin 61 farther out from the center point. In the third position of the pin, that is, when it is at the opposite side of the center point of the drive shaft to that shown in Fig. 3 the speed of rotation of the driven shaft will be higher than in the first position, the speed increasing each time an adjustment is made to pass the pin away in a 80 left hand direction (see Fig. 3) from the center point of the shaft.

In the actual machine I can so adjust the pin 61 that the driven shaft can be standing still while the drive shaft is rotated, that is, 85 the driven shaft will have zero speed and upon further adjustment of the pin in a right hand direction past the center of the drive shaft (see Fig. 3) I can effect reverse rotation of the driven shaft, increasing the 90 speed in the reverse direction from zero to a maximum speed equal to the speed of rotation of the drive shaft. Consequently with this machine, with a constant speed of rotation in the drive shaft, I am able to obtain any speed in the driven shaft in a forward direction from zero to maximum and a reverse rotation of the driven shaft at any speed from zero to the constant speed of rotation of the drive shaft. Further I can maintain any chosen or selected speed in the driven shaft in either the forward or reverse rotation by bringing the lever 54 to a central position once the selected speed is obtained. In the central position of the lever the pinion 53 is meshed with both the gear wheels 38 and 41. Accordingly the said gear wheels are locked so that they rotate together. The result of this is that no rotary motion is imparted to the shaft 44 as 100 the bevel pinion 43 automatically becomes locked between the bevel wheels 39 and 42 and as the plate 24 turns with the drive shaft the pinion 43 swings around the shaft but does not rotate and in swinging carries with it and consequently rotates both the bevel 105 wheels 39 and 42. The gear wheels 38 and 41 will rotate with the bevel wheels so that the counter shaft 46 is rotated. In this position it is free as neither of the faces of the friction disk are engaged with the cored recesses.

I wish now to explain why the machine acts to give, in the adjusted positions of the pin 61, the varying speeds of rotation in the driven shaft, graduating as selected from maximum positive forward to zero and from zero to maximum negative or reverse. In the first position of the pin, that is, with the pin adjusted so that it lies on the center 120

of the drive shaft the controlling wheel is obviously centered on the drive shaft. Further as motion is imparted to the drive shaft the disk is compelled to turn with the plate 5 24 through the action of the pins 29, 30 and 31 and it, the disk, actually swings in an eccentric manner as its center point "c" is eccentric to the point "d" which is at this time lying on the longitudinal axis of the drive 10 shaft. The eccentric swing given the disk while rotating with the shaft causes the carrying block to move and its movement is accommodated by the guide frames 13 and 16, which move one laterally and the other 15 vertically, the rods sliding in the framework. As the ring is fast to the block it moves with it and effects through the links an inward and outward movement of the shanks with the result that the dogs are brought into and 20 out of engagement with the wheel 62. Only one dog engages with the wheel at a time, but it is to be understood that as one dog is passing out of engagement the following dog is passing in. Accordingly in the central 25 position of the pin the controlling wheel is positively locked by the dogs against rotation on the pin. The result is that the pinion 72 is rotated around the bevel wheel 63 and in rotating carries with it the shaft 68 which in turn operates to rotate the shaft 57. The speed developed in the driven shaft is accordingly at this time entirely dependent on the ratio of the wheels 63, 72, 70 and 59.

30 When the pin 61 is in any one of the second adjusted positions, that is when it is to the right of the center point as shown in Fig. 3, there is a rotary motion on the pin imparted to the controlling wheel by the moving dogs, it being rotated in the same direction as the drive shaft with the result that the wheel 72 is turned slower and drives the cross shaft slower and so decreases the speed of rotation of the driven shaft. In 35 this connection I might remark that the speed of rotation of the controlling wheel in the above forward direction on the pin increases directly in proportion to the distance which the pin 61 is adjusted in a direction away from the center point of the drive shaft, and accordingly the speed of rotation of the driven shaft, in a forward direction decreases directly in proportion to the increased speed of the controlling wheel 40 on the pin. This action is so positive, the driven shaft can be brought to zero speed and then upon further adjusting the pin in an outward direction a reverse rotation can be obtained in the driven shaft, the reverse 45 speed increasing upon increased adjustment until it is equal to the constant drive speed of the drive shaft. In the third controlling position of the pin 61, that is, where it is to the left of the center point of the shaft, 50 (see Fig. 3) the controlling wheel is rotated

in a reverse direction to the drive shaft by the moving dogs. The result is that the speed of the pinion 72 is increased as it is swung around the controlling wheel and accordingly the shaft 68 rotates faster and in 55 rotating drives the driven shaft at a faster speed.

The action of the dogs in effecting the rotations above mentioned, forward and reverse, of the controlling wheel will be best 60 understood if reference be made to Fig. 4 wherein the pin is shown as adjusted considerably eccentric to the drive shaft. In the said figure it will be seen that the dog 84 is engaged with the wheel. As the drive shaft rotates and the pin with attached parts swings around the drive shaft the controlling wheel will be caused to rotate in a forward direction for the reason that the wheel 62 is engaged with the dog 84. At 65 the instant the dog 84 clears the wheel, the dog 75 engages with the wheel and in the swinging movement of the wheel with the pin rotates it. The dogs 76 and 83 following engage with and pass away from the 70 wheel in a like manner. It is to be noted that at no time is the wheel free as it is at all times engaged by one dog. Accordingly its movement, in so far as rotating around the pin is concerned, is constrained and 75 controlled directly by the dogs. The action of the dogs on the controlling wheel is the same when the pin carrying the controlling wheel is in the third position above mentioned, only the action of the dogs is such 80 that they cause the controlling wheel to rotate in an opposite direction on the pin in the swinging of the said wheel to that just described. The springs 91 serve to cushion the dogs as will be readily understood.

What I claim as my invention is;—

1. The combination with suitably mounted aligned drive and driven shafts, of a plate 110 permanently secured to the drive shaft and rotatable therewith, a pin carried by the plate and adjustable diametrically in respect to the longitudinal axis of the shaft, a controlling wheel rotatably mounted on the pin and embodying in its structure a gear 115 wheel and a bevel wheel, means engageable with the gear wheel in the various adjusted positions of the pin designed to effect and control the rotary movement of the controlling wheel on the pin in the rotation of the drive shaft and a driving connection between the bevel wheel and the driven shaft, as and for the purpose specified.

2. The combination with suitably mounted aligned drive and driven shafts, of a plate 125 permanently secured to the drive shaft, a disk carried by the plate and adjustable diametrically in respect to the longitudinal axis of the drive shaft, a pin extending from the disk, a controlling wheel mounted rotatably on the pin and embodying in its 130

structure a gear wheel and a bevel wheel, a carrying block mounted on the disk, slide-
5 able guide frames carrying the block, a ring concentric to the disk and secured to
the block, vertically and horizontally dis-
10 posed pairs of slidably mounted shanks ar-
ranged radially in respect to the longitudi-
nal axis of the drive shaft, links connect-
ing the ring with the shanks and effecting
15 the movement thereof in a radial direction,
toothed dogs located at the inner ends of
the shanks and engageable with the gear
wheel and a driving connection between the
bevel wheel and the driven shaft, as and for
15 the purpose specified.

3. The combination with suitably mount-
ed aligned drive and driven shafts, of a
20 plate permanently secured to the drive
shaft, a disk carried by the plate and ad-
justable diametrically in respect to the lon-
gitudinal axis of the drive shaft, a pin ex-
25 tends from the disk, a controlling wheel
rotatably mounted on the pin and embody-
ing in its structure a gear wheel and a bevel
wheel, a block receiving the disk, a sta-
30 tionary frame structure, horizontally and
vertically disposed guide frames carrying
the block, pairs of horizontally and verti-
cally disposed guide rods extending from
35 the respective frames and slidably mounted
in the framework, a ring arranged con-
centric to the disk and permanently secured
to the block, pairs of slidably mounted shanks
40 carried by the respective guide rods and
guide frames, said shanks being arranged
so that they radiate in respect to the lon-
gitudinal axis of the drive shaft, sleeves si-
45 dably mounted on the rods, links connecting
the sleeves with the ring, pins extending
from the outer ends of the shanks and en-
gaged with the outer ends of the sleeves, pins
50 passed through the bodies of the shanks,
spiral springs disposed on the shanks be-
tween the latter pins and the inner ends of
the sleeves, toothed dogs permanently
55 mounted on the inner ends of the shanks
and engageable in the rotation of the drive
shaft with the gear wheel of the controlling
wheel and a driving connection between the
bevel wheel and the driven shaft, as and for
55 the purpose specified.

4. The combination with suitably mount-
ed aligned drive and driven shafts, of a
plate permanently secured to the drive

shaft, a disk carried by the plate and ad-
justable diametrically in respect to the lon-
gitudinal axis of the drive shaft, a pin ex-
tending from the disk, a controlling wheel
rotatably mounted on the pin and embody-
ing in its structure a gear wheel and a bevel
60 wheel, a block receiving the disk, a sta-
tionary frame structure, horizontally and
vertically disposed guide frames carrying
the block, pairs of horizontally and verti-
cally disposed guide rods extending from
65 the respective frames and slidably mounted
in the framework, a ring arranged con-
centric to the disk and permanently secured
to the block, pairs of slidably mounted shanks
70 carried by the respective guide rods and
guide frames, said shanks being ar-
ranged so that they radiate in respect to the
longitudinal axis of the drive shaft, sleeves
75 slidably mounted on the rods, links connect-
ing the sleeves with the ring, pins extending
from the outer ends of the shanks and en-
gaged with the outer ends of the sleeves,
pins passed through the bodies of the
80 shanks, spiral springs disposed on the
shanks between the latter pins and the inner
ends of the sleeves, toothed dogs perma-
nently mounted on the inner ends of the
shanks and engageable in the rotation of the
85 drive shaft and the gear wheel with the
gear wheel of the controlling wheel, a bevel
wheel secured to the inner end of the driven
shaft, a carrying block rotatably mounted
on the driven shaft, a sliding frame mount-
90 ed on the carrying block, a square cross
shaft having the ends thereof carried rota-
bly by the sliding frame, a bevel pinion
permanently secured to the cross shaft and
meshed with the bevel wheel of the con-
95 trolling wheel, a second bevel pinion slid-
ably mounted on the cross shaft and
meshed with the bevel pinion at the inner
end of the driven shaft, and an arm secured
permanently to the latter carrying block
100 and holding the latter bevel pinion against
end movement on the cross shaft, as and for
the purpose specified.

Signed at Winnipeg this 6th day of July
1914.

JAMES ATKINSON DOUGLAS.

In the presence of—

S. GOULD,
G. S. ROXBURGH.
